WALDO E. ROSEBUSH, OF MILLWOOD, WASHINGTON.

EXHAUST SYSTEM FOR PAPER-MACHINE DRIERS.

Application filed May 19, 1926. Serial No. 110,220.

This invention relates to an improved system of exhausting the hot moist air from paper machine driers and has for an object to provide a simple construction which will efficiently remove the moist air from adjacent the driers while permitting new air to take the place of the moist air.

Another object of the invention is to provide an exhaust system for paper machine driers which will prevent condensation in the room containing the driers without the necessity of installing extra hot air pipes or other ventilating system.

A further object of the invention is to provide a system of exhaust for paper machine driers wherein the water from the moist air is condensed and the resulting hot water guided to places where the same may be used in the plant.

An additional object is to provide an exhaust system for removing moist air from driers wherein the heat in the air is conserved to a reasonable extent and the heated air again used.

Another object, more specifically, is to provide a construction wherein the moist hot air is separated at the source from the dry hot air through the use of a hood over the drier section of the paper machine.

In the accompanying drawings—

Figure 1 is a transverse sectional view through a shed or housing with certain mechanism shown in connection therewith, illustrating an embodiment of the invention.

Figure 2 is a sectional view through Figure 1, approximately on line 2—2.

Figure 3 is an enlarged detail view partly in elevation and partly in section, showing the exhaust pipes leading from the driers to condensing and other apparatus arranged above the driers, the section being taken on line 3—3 of Figure 1.

Figure 4 is an enlarged sectional view through Figure 3, approximately on line 4—4.

Figure 5 is a fragmentary sectional view approximately on line 5—5 of Figure 4.

Figure 6 is an enlarged side view of a number of driers together with the hoods arranged thereon and certain associated parts embodying certain features of the invention.

Figure 7 is an enlarged detail fragmentary sectional view showing the formation of one of the suction heads.

Figure 8 is a bottom plan view of the head shown in Figure 7.

In forming the construction embodying the invention, a hood structure is arranged to enclose or partly enclose the various driers and the hot moist air is drawn up into this hood structure and exhausted out through a pipe leading preferably to a point above the building in which the driers are located. The exhaust air is laden with moisture and is also comparatively hot. After the exhaust air reaches the desired point above the building, it is passed through certain cleaners hereinafter more fully described whereby the moisture is removed to a large extent and the air is also cooled to a certain extent. This cooled and somewhat dried air is then forced downwardly to a desired point, heated and then again released in the room where the driers are located. The releasing of the heated comparatively dry air in the room prevents condensation on the walls of the room and permits air to pass to the driers to take the place of the hot moist air drawn therefrom into the hood. This method of circulating the air and conserving the heat is very desirable as it provides hot water for use in the plant using the driers and also conserves fuel by using the heated air over and over. In the drying of paper, it has been found that for every pound of paper taken from the dry end of the machine, two pounds of water are evaporated from the web of the paper in its passage through the drier stack. The paper comes to the wet end of the driers, usually in all machines, at an approximate moisture content of around seventy per cent for the manufacture of most papers, especially newsprint. The passage of the paper through the driers is for the purpose of removing moisture from the wet web so that the sheet will have a resultant wet content of approximately seven or eight per cent.

It will, of course, be evident that the drier, gears, frame, etc., become heated to an appreciable degree by the radiation and conduction of heat from the inner portion of the machine, namely, from the drier shell. The heat emanating from these principal portions, namely, the frame, etc., does not contain moisture in the same sense that the heat emanating from the inner portions of the machine does. In other words, it is dry heat and as such can absorb a large amount

- 2 of moisture. This dry heat by reason of the construction involved is allowed to remain in the room and rise to the roof and spread out over the room so as to tend to conserve 5 the amount of air necessary to be handled in order to keep the room dry and free from condensation. This heat also in the winter time would provide almost enough heat to keep the room at a comfortable temperature.
- 10 To properly regulate the ventilation in the room containing the driers, the building is preferably provided with a number of sashes in the roof which may be controlled from the floor.
- 15 In Figure 1, a cross section is shown through a building equipped with a number of driers and with an exhaust system disclosing an embodiment of the invention. From this figure it will be seen that the 20 building 1 is provided with a room 2 in which the various driers 3 are arranged. A floor 4 is provided which is open below the various driers 3, so that air may freely enter and pass upwardly to the driers from the 25 basement 5. It will be noted that the building 1 is provided with side walls 6 and a top or roof structure 7. The driers 3 may be of any desired or preferred construction and include a number of drying steam rollers 30 and also a number of felt rollers whereby the paper may be properly guided and dried in an approved manner. The specific construction of the driers forms no part of the present invention.
- 35 In connection with each series of driers there is arranged a hood 8 which is preferably formed into sections 9 for easy mounting, though the hood could be made as one structure without departing from the 40 spirit of the invention. Associated with the hood 8 are side walls or plates 10 (Figure 4.) These side walls or plates extend downwardly to near the lower felt roller 11. It will thus be seen that practically all the 45 space where the steam rises from the driers is enclosed by the plates 10 in association with the hood 8. Below the plates 10 there is ample room for workmen to reach in and remove pieces of paper from the various 50 rolls. Also, the lower parts of the driers are exposed so that the machine may be properly threaded from time to time. The hood 8 may be supported in any desired manner, as for instance, by suitable angle 55 iron uprights and in fact, the hood 8 is preferably made with a frame of ribs of angle iron with sheet material covering the same. The lower wall or bottom of the hood is, however, made of corrugated metal 60 plates 12 as shown particularly in Figure 6. In each of the sections 10 there is preferably arranged two doors, namely, doors 13 and 14. These doors are pivotally mounted in any suitable way, as for instance, by being 65 secured to rods 15 extending through the side walls of the hood. Each of the rods 15 is provided with a turned up portion 16 (Figure 4) which acts as a handle whereby any of these doors may be opened or all may be opened or partly opened as desired. The 70 corrugated bottom 12 is preferably used as it naturally prevents a tight connection with the side walls so that there will always be a small space whereby the moist air may pass upwardly against the top wall or roof 75 of the hood 8 and then over the bottom 12 even though the doors 13 and 14 may be closed.
- In order to provide a suction near the lower felt rollers 11, there is provided a 80 pair of pipes 17 for each roller 11 and at the end of each of these pipes there is provided a head 18 having an inclined face 19, said inclined faces being perforated as shown in Figure 8. Each of the pipes 17 extends upwardly through the bottom 12 so that they are continually exhausting into the hood 8. When the device is in use, the various doors 13 and 14 are also either entirely open or partly open according to their 85 location in respect to the driers and also according to certain other conditions. The hood 8 extends for the full length over all of the driers in a given series and at a desired point there is provided an exhaust pipe 20 whereby the hood 8 is exhausted. Preferably, the parts are so proportioned and operated that there will be a slight suction or rarefaction in the hood 8 at all times. 90 This will cause the liberated moisture from the driers to gradually and immediately move upwardly and away from the rollers whereby a maximum drying effect is secured. Preferably, the exhaust pipe 20 is connected with hood 8 at about two-thirds the distance 95 from the entrance of the wet paper into the drying machines, though the position of the exhaust pipe may be shifted or varied as desired. The position is preferably as described because the wet paper first 100 entering the machine does not give off much moisture until it has passed several of the drying rollers. By locating the exhaust pipe 20 as described, the same is positioned at 105 about the point where most of the moisture is given off and, consequently, an efficient exhausting is secured. If there is more than one series of driers 3 in the building 1, as for instance, three, as illustrated in Figure 110 1, each of these driers is provided with a hood 8 and each is provided with an exhaust pipe 20. These various exhaust pipes merge into the main exhaust pipe 21 which 115 extends through the roof 7 and horizontally along the roof to a desired point. At the point of bending of pipe 21, there is provided a spray nozzle 22 as shown in Figure 120 3. This nozzle is provided with cold water through suitable pipes or hose 23 and 24 which may be controlled in any desired man-

ner. The nozzle 22 is set so as to discharge a whole spray of water horizontally into the pipe 21 and this spray assists in producing a condensation of the hot vapors. In addition to spray 22, there is provided a series of sprays 25 at various points along pipe 21. This additional spray of cold water causes an additional reduction in the temperature of the air and moisture therein so that the water laden air entering the air washer 26 will be easily deprived of most of the water therein so that the air entering the fan 27 will be almost free of water and cooler though still at a rather high temperature. The air washer 26 may be of any standard kind, as for instance, what is commonly known on the market as the "Western." This washer contains a number of baffle plates maintained cool by water and also by air. The fan 27 is driven by any suitable means, as for instance, an ordinary electric motor 28. This fan discharges into a series of members 29 known as eliminators. These eliminators are maintained cool by a spray of water from the spray member 30 which is supplied with water through pipe 31, which pipe in turn is supplied with water through the pipe 32. The pipe 32 may be supplied with water from any suitable source and if desired, pressure. The eliminators 29 present in fact substantially the same structure as the air washers 26 and are used to remove additional moisture from the air after they leave fan 27. After the air leaves the structure 33 containing the eliminators 29, it passes into a pipe 34 and from thence downwardly to the basement 5. An air valve 36 is provided in pipe 34 so as to control the movement of air therein. Sometimes it is desired to add fresh air from the atmosphere and, consequently, a pipe 37 is connected with pipe 34, said pipe 37 extending through the wall 38. An air valve 39 is arranged in pipe 37 so as to vary the amount of air supplied through this pipe. By the method just described, the hot moist air is exhausted or drawn away from the driers, moved to a position on the roof of the building, deprived of a large percentage of the moisture therein and some of the heat though not all. The comparatively dried air which is still comparatively warm, is forced downwardly through the pipe 34 to a heater 40 which may be of any desired construction. A series of shutters 41 is arranged in pipe 34 near heater 40, said shutters opening to the atmosphere whereby additional air may be drawn in at this point if desired. After the air has passed through the heater 40, it enters the fan casing 42 and is forced by the fan upwardly and through the various pipes 43 to the discharge openings 44. It will be noted that the pipes 43 extend to near the walls of the building 1 as shown in Figure 2 and discharge the heated air against the walls. This will cause the heated air to pass upwardly along the walls and from thence over the interior surface of the roof. This arrangement is very desirable as it prevents condensation in the room 2 where the driers 3 are located. It will be noted that the fan 27 produces the desired suction or rarefaction in the hood 8 and associated parts and at the same time forces the cleaned or more or less dried air downwardly into the heater 40. Fan 42 acts to force the heated air into the room 2 and preferably the fan 42 acts in a manner to maintain a slight pressure in room 2 above atmospheric pressure. This will prevent any air entering room 2 other than through the pipes 43 whereby an even action of the driers may be secured. It will also be noted that the air cleaner 26 really is a condenser for removing the moisture from the air and the resulting water may be drawn off through a suitable pipe and used as desired.

In regard to the fan 27, it will be noted that in case this fan is operating at a greater capacity than the fan in the basement, the excess air escapes out of the condenser 33 which is really a series of eliminator plates and a casing having suitable openings. If for any reason, fan 27 should not be operating at the capacity of the fan in the basement, the difference required to satisfy the lower fan can be secured by air drawn through the condenser 33 or by air drawn through the pipe 37.

What I claim is:

1. A system of exhausting the hot moist air from paper machine driers including a hood adapted to fit partly over the driers, means for exhausting the hot moist air from the hood and directing the same to a distant point, means at said distant point for condensing the moisture in said air and reducing somewhat the temperature of the air, means for causing the cooled and comparatively dried air to be forced to a heater, means for heating the air at said heater, and means for directing the heated air into the room in which the driers are located, said means directing the air so that it will pass upwardly along the side walls and along the under side of the roof for preventing condensation.
2. A system of exhausting hot moist air from paper machine driers including means forming a building in which the driers are located, a hood for said driers, a fan for exhausting air from said hood, a condenser for condensing water in the air, a heater, means for directing the air after the water has been condensed therefrom whereby the air will enter said heater, and means including a fan for forcing the air from the heater so that it will spread over the interior side walls of said building and the interior surface of the roof for preventing condensation.

and at the same time providing heated air adjacent the driers.

3. A system of exhausting the hot moist air from paper machine driers including a hood for receiving the hot moist air directly from the driers, a pipe for directing the hot moist air to a condenser, means for spraying cooling water into said pipe for reducing the temperature of the air, a heater for said air, means for forcing the air from said condenser to said heater, said means including a second condenser for eliminating additional moisture from the air, and means for directing the heated air into the room in which the driers are located, said means directing the air so that it will pass along the walls and along the under side of the roof for preventing condensation.

4. A system of exhausting the hot moist air from paper machine driers including a building for receiving the driers, means for removing the hot moist air from the vicinity of the driers, means for condensing the moisture in said air, a heater, means for directing the air to the heater after the moisture has been condensed therefrom, and means for directing the heated air from said heater to points near the side walls of said building whereby condensation on the walls and roof of the building is prevented and the room in which the driers are mounted is supplied with comparatively dried heated air.

5. In a system of exhausting the hot moist air from paper machine driers a hood for the

driers, said hood including a pair of side plates overlapping an appreciable part of the driers, said hood being formed with a bottom structure extending over the driers, said bottom structure having a series of manually actuated doors whereby the openings between the doors and the hood may be varied, and means for exhausting the hot moist air from said hood.

6. In a system of exhausting hot moist air from paper machine driers a hood having enclosing means extending over part of the driers, said hood also being formed with a series of depending pipes extending to a point adjacent the point of liberation of moisture from the driers, each of said pipes having a perforated head at the intake end while at the opposite end the pipes exhaust into the hood, and means for exhausting said hood to a distant point.

7. In a system of exhausting hot moist air from paper machine driers a hood for the driers, said hood including a series of depending pipes extending to a point intermediate the height of the driers, said hood also including a floor arranged above the driers, said floor being formed with a series of doors, manually actuated means for opening and closing the doors whereby the amount of suction through the doors may be varied, and means for exhausting the hot moist air from the hood and discharging the same at a distant point.

WALDO E. ROSEBUSH.
